UNITED STATES PATENT OFFICE.

BURTIS VAN HENNIK, OF NEW YORK, N. Y.

PACKAGE-ELEVATOR.

SPECIFICATION forming part of Letters Patent No. 449,453, dated March 31, 1891.

Application filed August 1, 1890. Serial No. 360,695. (No model.)

To all whom it may concern:

Be it known that I, BURTIS VAN HENNIK, of New York city, in the county and State of New York, have invented a new and Improved 5 Package-Elevator for Presses, of which the following is a full, clear, and exact description.

My invention relates to a package-elevator for presses, and has for its object to provide 10 a means whereby packages of paper to be printed may be expeditiously and conveniently elevated from the floor of the press-room and delivered alongside of the feed-table of the press with a minimum of inconvenience to the attendants of the press; and 15 a further object of the invention is to provide a means whereby the elevated packages may be readily transferred from the elevator to the feed-table.

Another object of the invention is to provide 20 a device capable of accomplishing the above-named results which may be set up in any press-room, occupying space not heretofore utilized, and to so simplify the device 25 that it may be constructed and erected at but little cost and attended by unskilled labor.

The invention consists in the novel construction and combination of the several parts, as will be hereinafter fully set forth, and 30 pointed out in the claims.

Reference is to be had to the accompanying drawings, forming a part of this specification, in which similar figures and letters of reference indicate corresponding parts in all the 35 views.

Figure 1 is a perspective view of the elevator, the lifting-platform being represented as in position to receive a package. Fig. 2 is a perspective view of the elevating mechanism, the elevator being illustrated as carried 40 upward and the package as in position to be slid upon the feed-table; and Fig. 3 is a transverse section through the elevator-table and its carrying-frame, illustrating the said table 45 in position to admit of the transfer of the paper to the feed-table.

Tracks 10, usually two in number, are suspended from the ceiling or other support at the rear of the feed-table 11 of the press or 50 presses, which tracks are inclined downward at one end in the direction of the table, as is

best illustrated in Fig. 2. The tracks may be of any desired contour in cross-section, and upon the tracks a carriage A is held to travel, which carriage consists, preferably, of four corner posts or uprights 12, connected by cross-bars 13 and braced by diagonal bars 14. Each of the corner posts or standards has formed integral with its lower end or attached thereto a hook 15, the mouth of the hooks being somewhat diagonally inclined, as is best shown in Fig. 1.

In suitable bearings at the upper end of each of the corner posts or standards of the carriage a friction roller or wheel 16 is journaled, which wheels are adapted for engagement with the tread of the track, the said wheels or pulleys being usually provided with a peripheral groove to receive the same.

To the forward end cross-bar of the carriage one end of a rope 17 or chain is secured, the attachment of the chain being preferably at the central portion of the said end, and the said rope or chain is carried forward between the tracks to a point at or near the ends of the latter and downward over a friction-pulley 18 or equivalent device pivoted in any approved form of hanger, and from the friction-pulley 18 the cord 17 or chain is carried vertically downward and attached to an eye 19 or its equivalent secured to the floor of the press-room, for instance. The said cord or chain is also preferably provided with a ring or eye 20, secured thereto between the friction-pulley 18 and its lower 85 attached end.

At or near the forward or upper end of the tracks a drum 21 is pivoted in suitable bearings 22, the said drum being preferably made to extend transversely below the tracks. The drum has integral with or attached to one end a peripherally-grooved wheel 23, and to the periphery of the said wheel one end of a rope 24 or chain is secured, the other end of the said rope or chain being attached to a windlass 25 or its equivalent, as illustrated in Fig. 1; but, if in practice it is found desirable, the rope or chain may be passed around the wheel 23 of the drum, and thence around a lower friction-pulley, in which event 100 the chain or rope is endless.

Near one end of the drum two cords a and

a' or chains are secured, and at or near the opposite end two other cords *a²* and *a³* are secured. The cord *a'* or chain passes through screw-eyes and over friction-rollers 26 and 27, 5 somewhat closely grouped and secured to the ceiling or other support to which the tracks are attached, and after passing over the inner friction-pulley 27 the cord *a'* or chain is permitted to fall vertically downward. The second cord *a* or chain of this pair is also carried over friction-rollers 28 and 29, suspended from the ceiling; but the friction-roller 29 is a much greater distance from the friction-roller 28 than the friction-roller 27 is distant from the friction-roller 10 26. After passing over the friction-roller 29 the cord *a* or chain is also permitted to drop perpendicularly downward. The cords *a²* and *a³* or chains are passed over friction-rollers in like manner to the cords *a* and *a'* at the opposite 15 site end of the drum, and which have just been described, the position of the friction-rollers over which the rope *a²* or chain passes corresponding in position to the friction-rollers 26 and 27 of the cord *a'* or chain, and the friction-rollers of the cord *a³* or chain correspond in location to the friction-rollers 28 and 29 of the cord *a* or chain.

The lower extremities of the cords *a*, *a'*, *a²*, and *a³* or chains are attached one at each corner of a platform 30, which platform, together with the cords, constitutes an elevator B. The platform 30 is preferably made as light as possible consistent with strength, and in the drawings is represented as constructed of two 35 side bars having eyes formed at their extremities, through which the cords or chains are passed, the said side bars being connected by diagonal brace-bars, as is best shown in Fig. 2.

40 In connection with the elevator and carriage a paper-carrying table C is employed. The table is preferably made in two sections—namely, a platform-section 31 and a frame-section 32, the former being fitted into the latter. The frame-section corresponds in contour to the contour of the platform-section, which is preferably rectangular, and the frame-section 32 is ordinarily made of skeleton form and provided at each corner with an 45 upwardly-extending preferably perpendicular standard 33, each of which standards is provided at or near its upper extremity with a longitudinal slot 34. When the elevator-platform B is constructed as described, the 50 side bars of the frame-section of the table are provided with recesses to receive the transverse bars of the elevator-platform. The platform-section 31 consists, preferably, of one piece of metal, wood, or other preferred material, and is usually divided transversely 55 into two compartments by a partition 35. At one side of the platform-section of the table and at both ends upright studs 36 are secured to the upper face, as best shown in Fig. 1, and at that side of the platform-section which 60 faces the press feed table or tables studs 37 are located, which studs are preferably

hinged or pivoted to the platform-section in such manner that they are capable of folding downward and outward, as shown in Fig. 3. 70 The construction of the movable studs, as illustrated in the drawings, consists in providing the inner end of each stud with a longitudinal slot 38, and the studs are located in metal-lined recesses 39, the pivot-pin of the 75 studs being secured in the walls of the recesses and made to pass through the slots 38, as is likewise best shown in Fig. 3.

In operation the table C, seated in its frame, is placed upon the elevator-platform B when 80 the said platform is resting upon the floor of the press-room, and when the table is in this position the desired number of packages of paper to be printed are placed upon it. The carriage A is then drawn up the inclined 85 tracks until it is near the forward end of the latter. When the carriage is in proper position, it may be held so by causing the ring 20 of the rope 17 or chain connected with the carriage to engage with a hook or equivalent 90 device placed in the floor to receive it, as illustrated in Fig. 1, and when the carriage is secured in proper position it will be immediately above the table, as shown in the same figure. By operating the windlass or the cord 95 24, connected with the drum 21, the said drum is revolved and the lifting-cords *a*, *a'*, *a²*, and *a³* or chains are wound upon the drum, and the elevator is thereby carried upward beneath the carriage. As the elevator-platform 100 approaches the carriage the slots 34 in the uprights 33 of the table-frame receive the hooks 15 of the carriage, whereupon the frame and table become a portion of the carriage, and by loosening the rope 17 or chain the carriage is permitted to travel down the inclined 105 plane of the tracks until it reaches one of the press feed-tables, as illustrated in Fig. 2, at which point it may be stopped in any suitable or approved manner, and the pivoted 110 studs 37 are thrown downward upon the press-table, as shown in Fig. 3, and the operator at the feed-table may thereupon expeditiously slide the packages of paper from the table of the carriage to the said feed-table. When 115 the packages have been delivered to the press or presses, the cord or rope 17 is again drawn downward and the carriage is brought over the elevator-platform. The windlass is then operated, and the platform of the elevator is 120 lifted upward sufficiently to engage with and elevate the frame carrying the platform-section of the table C, and in thus lifting the frame the slotted standards of the latter are disengaged from the hooks of the carriage, 125 and in disengaging the standards cause the carriage to slide slightly forward as the tops of the standards come into engagement with the inclined surfaces of the hooks, and by pushing the carriage a slight distance forward it is removed from the path of the table C, whereupon the elevator may be lowered to 130 carry the table with it to the floor of the press-room to receive another load.

Having thus described my invention, I claim as new and desire to secure by Letters Patent—

1. In a package-elevator, the combination, with a carriage adapted to travel upon suspended tracks, of an elevator and a package-carrying table adapted to be supported by the elevator-platform and to be engaged by the carriage when raised, whereby provision is made for raising the package-carrying table and transferring it from the elevator-platform to the carriage, substantially as described.
2. In a package-elevator, the combination, with a carriage adapted to travel upon suspended tracks, of a platform and means for raising and lowering said platform and a package-carrying table adapted to be supported upon the platform and provided with means for engaging the carriage when elevated, substantially as herein shown and described.
3. In a package-elevator, the combination, with a carriage adapted to travel upon suspended tracks, of a platform, a drum, means for operating the drum, cords attached to the drum, passed over pulleys, and attached to the said platform, and a package-carrying table adapted to be supported on the platform and provided with means for connecting it when elevated to the carriage, substantially as described.
4. In a package-elevator, the combination, with an inclined track and a carriage traveling on said track and provided with hooks, of a platform, a drum, cords attached to the

drum, passed over pulleys, and connected to the platform, a package-carrying table adapted to be supported on the platform and provided with standards having openings to engage the hooks of the carriage, and means for operating the drum and carriage, substantially as herein shown and described.

5. In a device of the character described, the combination, with a carriage capable of lateral movement and an elevator, of a package-carrying table adapted for removable engagement with the elevator and with the carriage and studs pivotally attached to the table, as and for the purpose specified.

6. In a device of the character described, the combination, with inclined tracks and a carriage held to travel upon the tracks, of a table comprising a platform-section and a supporting frame-section, the latter section being provided with means for automatic engagement with the carriage, as and for the purpose specified.

7. In a device of the character described, the combination, with a carriage capable of lateral movement, of a package-carrying table comprising a platform-section and a supporting frame-section, the latter section being provided with means for automatic engagement with the carriage, and an elevating mechanism, as and for the purpose set forth.
